UNITED STATES PATENT OFFICE.

GUSTAVUS A. SCHLECHTER, OF READING, PENNSYLVANIA.

DESIGN FOR A MEDAL.

SPECIFICATION forming part of Design No. 21,146, dated November 3, 1891.

Application filed September 4, 1891. Serial No. 404,774. Term of patent 3½ years.

To all whom it may concern:

Be it known that I, GUSTAVUS A. SCHLECHTER, a citizen of the United States, residing at Reading, in the county of Berks, State of Pennsylvania, have invented a certain new and original Design for Medals, of which the following is a specification.

The accompanying drawing fully illustrates my design.

- 10 The medal or badge is shown as formed of two parts, the bar A and pendant B, suspended therefrom. The bar represents a bow having three arrows crossing one another in the center thereof, while a plane surface is provided between the heads and tails of the arrows, which may be used for any desired lettering. The pendant is a circular disk, in the center of which appears the letter, on a dark background, of triangular form, which is inclosed
- 15

by a triangle of similar shape. Between these triangles is sufficient space for lettering. Circumscribed about the larger triangle is a circular band, on which are certain initial letters, while between said band and the larger triangle are representations of a bow and arrows, crossed swords, and a manna-cup. The circular band is in turn circumscribed by a square, within the four corners of which is additional space for lettering.

What I claim is—

The design for a medal, substantially as herein shown and described.

In testimony whereof I affix my signature in presence of two witnesses.

GUSTAVUS A. SCHLECHTER.
